UNITED STATES PATENT OFFICE.

LEONIDAS D. WEST, OF DUNDEE, NEW YORK.

ATTACHMENT FOR HEATERS.

SPECIFICATION forming part of Letters Patent No. 663,987, dated December 18, 1900.

Application filed February 6, 1900. Serial No. 4,161. (No model.)

To all whom it may concern:

Be it known that I, LEONIDAS D. WEST, of Dundee, in the county of Yates, in the State of New York, have invented certain new and useful Improvements in Attachments for Heaters, of which the following is a specification.

My invention relates to a new and useful article of manufacture, consisting of an attachment for heaters, and has for its object the production of a simple and practical device which may be readily attached to any form of heater, and particularly to stoves, ranges, and furnaces, for the purpose of facilitating combustion within the combustion-chamber and for otherwise rendering the heater more efficient and economical in operation.

To this end the invention consists in the construction and arrangement of the component parts of an attachment for heaters, as hereinafter fully described, and pointed out in the claims.

Figure 1 is a perspective view of my invention shown as operatively attached to a heater, as a range, illustrated by dotted lines. Figs. 2 and 3 are respectively enlarged side and front elevations of the device seen in Fig. 1, the damper for controlling the passage of the products of combustion being shown in its open position. Fig. 4 is a sectional view taken on line 4 4, Fig. 2. Figs. 5, 6, 7, 8, and 9 are sectional views taken, respectively, on lines 5 5, 6 6, 7 7, 8 8, and 9 9, Fig. 3. Fig. 10 is a side elevation similar to Fig. 2, the damper of the smoke-conduit being shown in a different position from that seen in Fig. 2. Fig. 11 is a sectional view taken on line 11 11, Fig. 10. Figs. 12 and 14 are enlarged elevations of the dampers for controlling the inlet of air to the heating-chamber and to the smoke-conduit and the supporting-walls adjacent thereto. Figs. 13 and 15 are sectional views taken, respectively, on lines 13 13 and 15 15, Figs. 45 12 and 14; and Figs. 16 and 17 are face views, one being partly in section, of a slightly modified form of my invention.

This invention consists, essentially, of a section A of a smoke-conduit, and a chamber B, interposed between the opposite ends of said section and preferably supported thereby, for receiving a supporter of combustion,

as air, and conveying the same to the interior of the smoke-conduit or directly to the combustion-chamber of the heater through a separate conduit arranged within the smoke-conduit, as may be desired.

The invention further consists in the means provided on the section A for controlling the passage of the supporter of combustion, as atmospheric air, to and from the chamber B and in additional means, also provided on the section A, for controlling the draft and the passage of gases therethrough when the section A is attached to the heater, as a range C, Fig. 1.

The section A may be of any desired form, size, or material, but usually consists of a sheet-metal cylindrical drum having its opposite ends formed of substantially uniform size in order that the same may be readily and economically attached as a whole to standard sizes of smoke pipes or conduits of stoves, ranges, or other heaters by simply substituting the same for one of the lengths of pipe or smoke-conduit of the heater. It is thus apparent that when my device is placed in operative position the section A forms one of the sections of the smoke-conduit usually in proximity to the heater, so that the movable parts of my invention may be readily and conveniently manipulated.

The chamber B preferably encircles the intermediate portion of the section A, is provided with an inlet-opening b, outlet-openings b' b'', and is surrounded by a drum b³, inclosing a portion b⁴ of the section A, said drum b³ and the portion b⁴ of the section A forming the outer and inner walls of the chamber B. The opposite ends of the chamber B are closed by suitable walls which unite the upper and lower ends of drum b³ to the section A and form a convenient and efficient support for said drum b³.

The inlet-opening b, as illustrated, is arranged at the upper end of the chamber B, extends through the wall of the drum b³, and communicates with an inlet-chamber b⁶, having an inlet-opening b⁷ communicating with the atmosphere or other supporter of combustion. The opening b⁷ is closed by a suitable closure E, preferably hinged to the walls of the chamber b⁶, for controlling the entrance of air or other supporter of combustion to

the chamber B. When the draft through the smoke-conduit A is excessively strong or the expansive force of the gases within the combustion-chamber and smoke-conduit produces an excessive inequality of pressure therein, thus causing the unburned gases and fuel to escape through the smoke-conduit, the damper E may be opened to its full or partial capacity, whereupon the air enters the chamber B and is discharged therefrom to the combustion-chamber in a heated state for facilitating combustion and consuming the unburned products before reaching the smoke-conduit A. It has been demonstrated, however, that under ordinary conditions of draft and heat within the combustion-chamber only a small amount of air, if properly heated before entering the combustion-chamber, is necessary to perfect an economical combustion and that the force of the expanding gases or draft in the combustion-chamber is generally only sufficient to draw in a small amount of air. I therefore provide the inclosure E with a plurality of small apertures e' and a supplemental inclosure e^2 for controlling the entrance of air through the apertures e' when the former closure E is in its normal position, thereby affording a means for supplying a quantity of heated air or other supporter of combustion to the combustion-chamber proportionate to the requirements for perfect and complete combustion.

The outlet-openings b' b^2 , as illustrated in the drawings, Figs. 7 and 11, are arranged in close proximity to the lower wall of the chamber B, the outlet-opening b' being extended through the base of the drum b^3 for receiving a conduit, (not shown,) which may be arranged at the outside of the smoke conduit or section A and lead directly to the combustion-chamber of the heater. The outlet-opening b^2 usually consists of a series of perforations extending through the base of the inner wall b^4 of the chamber B for conducting the air or other supporter of combustion, previously heated in transit through the chamber B, to the interior of the section A, whereby said heated air is conducted to the contiguous lower section, as c , forming a continuation of the section A, and thence to the combustion-chamber of the heater. It will be understood that both of the outlet-openings b' b^2 may be simultaneously connected to the combustion-chamber and that either of said outlet-openings may be used independently of the other. When the outer conduit is used alone, the outlet-opening b^2 may be closed by a suitable closure F, having perforations f movable into and out of registration with the apertures b^2 , and when desired to discharge the heated air into the interior of the section A independently of the external opening b' the perforations f are registered with the aperture b^2 and the opening b' is closed by a suitable cap, as b^5 .

In order that the highest degree of efficiency

may be attained from my invention when the igneous material is well ignited, I provide the section A with a suitable damper D, preferably arranged above and in proximity to the heating-chamber B and usually mounted on a rock-shaft d , extending through the walls of the section A. When the combustion is well under way, the damper D is wholly or partially closed, thereby checking the escape of the products of combustion and additionally heating the air in the chamber B before entering the combustion-chamber of the heater. It has been further demonstrated that the degree of pressure in the combustion-chamber fluctuates with the variations of the draft through the smoke-conduit and that it is necessary, as previously stated, to have the supply of heated air proportionate to the pressure in order to produce perfect combustion. I therefore provide the section A with an opening a^2 , preferably arranged above and in proximity to the damper D and connecting with a chamber g , having an inlet-opening g^4 communicating with the atmosphere. G is a damper for controlling the passage of air through the inlet-openings g^4 a^2 , is hinged to the walls of said chamber g , and consists of upper and lower sections g^2 and g^3 , the upper section g^2 being hinged to the walls of the chamber g and the lower section g^3 being hinged to the outer face of the upper section above its bottom edge in order that when the section g^2 is in its normal inclosed position the section g^3 is held from movement and positively closes the opening g^4 . When the draft through the smoke-conduit A is excessive or fluctuating, the upper section g^2 is rocked inwardly, whereupon the lower section g^3 is free to swing in the chamber g for automatically controlling the volume of air admitted through the openings g^4 and a^2 , according to the intensity of the draft, and thereby maintaining a substantially uniform pressure in the combustion chamber and consequent uniform amount of heated air passing through the chamber B. The dampers D G and the closure E may be operated in any desired manner and are preferably connected to a suitable operating member D' by connections, as chains d^3 g^5 e^4 . The operating member D' is pivoted at its intermediate portion to the walls of the lower portion of the section A beneath the chamber B, is mounted on a shaft extending through the walls of the section A and a sleeve a interposed between said walls, and is provided with a shoulder d^4 , frictionally engaged with a shoulder a' on the section A, arms d^5 and d^6 , connected, respectively, to the lower ends of the chains d^3 g^5 , and a sliding connection d^9 , connected to the lower end of the chain d^4 and movable on a suitable guide d^7 , extending lengthwise of the arms d^5 . The shoulders d^4 a' are held in frictional engagement by a spring d^8 for preventing undue movement of the operating member D' . The

upper ends of the chains d^3 g^5 e^4 are connected, respectively, to arms d^2 g^6 e^3 for controlling the position of the dampers D and G and the closure E, which are held in their normal positions by suitable weights d' , g' , and e . The above-described operating means for the dampers D and G and the closure E are not essential to the successful operation of my device, and it is therefore unnecessary to further illustrate or describe the same.

In Figs. 16 and 17 I have shown two heating-chambers B^{40} and B^{41} connected to each other, the chamber B^{40} being provided with a tortuous conduit b^{40} , having an extension b^{41} adapted to discharge into the combustion-chamber. (Not shown.)

The operation of my invention is substantially the same as set forth in my pending application for process, Serial No. 13,424, except in the present instance I have shown my device as attached to a range C, consisting of an inclosing shell C' , provided with inlet-openings C^2 , leading to the combustion-chamber and with a closure C^3 for controlling the entrance of air through said openings. When my device is used in connection with a range, as illustrated in Fig. 1, the operation is as follows: When the igneous material is first ignited, the closure C^3 and the damper D are opened and the closure E and damper G are closed for permitting the smoke and gases to escape freely through the section A without liability of the escape of any gases or smoke into the room in which my device is located, the supply of air to the combustion-chamber being admitted directly through the openings C^2 . When the combustion is well under way, the inlet-openings C^2 are closed, the expanding heated products of combustion rise through the smoke-conduits A c, and produce an inequality of pressure in the combustion chamber and air-chamber, whereupon air is admitted through the restricted apertures e' or inlet-opening b to the chamber B, which air is heated in said air-chamber and is drawn through the outlet-openings b' or b^2 , as may be desired, to the combustion-chamber of the heater by the inequality of pressure in said combustion-chamber, which forms a connection between the air-chamber and smoke-conduit.

The operation of my invention will now be readily understood upon reference to the foregoing description and the accompanying drawings, and it will be noted that considerable change may be made in the detail, construction, and arrangement of the parts of my invention without departing from the spirit thereof. Therefore I do not herein limit myself to the precise construction and arrangement shown and described.

Having thus fully described my invention,

what I claim as new, and desire to secure by Letters Patent, is—

1. As a new article of manufacture, an attachment for heaters for the purpose described, the same comprising a section of a smoke-conduit provided with an opening, a closure for the opening, a drum encircling the intermediate portion of the smoke-conduit beneath said opening for forming an air-chamber surrounding the smoke-conduit, said chamber being provided with an inlet-opening communicating with the atmosphere and an outlet-opening communicating with the interior of the conduit, a closure for the inlet-opening and a damper arranged within the smoke-conduit between said openings.

2. As a new article of manufacture, an attachment for heaters for the purpose described, the same consisting of a section of a smoke-conduit provided with an opening, a closure for the opening, means for automatically closing said closure, a drum encircling the intermediate portion of the conduit for forming an air-chamber surrounding the conduit, said air-chamber being provided with an inlet-opening communicating with the atmosphere and an outlet-opening communicating with the interior of the conduit, a closure for the inlet-opening, means for automatically closing said closure, and a damper arranged within the smoke-conduit between said openings.

3. As a new article of manufacture, an attachment for heaters for the purpose described, the same consisting of a section of a smoke-conduit provided with an opening, a closure for the opening, means for automatically closing said closure, a drum encircling the intermediate portion of the smoke-conduit for forming an air-chamber surrounding the conduit, said air-chamber being provided with an inlet-opening communicating with the atmosphere and an outlet-opening communicating with the interior of the conduit, a closure for the inlet-opening, a damper arranged within the conduit between said openings, means for automatically closing the damper, and an operating member having opposite arms connected respectively to the closure of the first opening and to the damper and provided with an adjustable slide connected to the closure for the inlet-opening.

In testimony whereof I have hereunto signed my name, in the presence of two attesting witnesses, at Syracuse, in the county of Onondaga, and in the State of New York, this 27th day of January, 1900.

LEONIDAS D. WEST.

Witnesses:
